[57] **CLAIM**

The ornamental designs for a shoe outsole, as shown and described.

DESCRIPTION

FIG. 1 is a bottom plan view of a Shoe Outsole, showing my new design;

FIG. 2 is a right side elevational view thereof;

FIG. 3 is a left side elevational view thereof;

FIG. 4 is a front elevational view thereof; and,

FIG. 5 is a rear elevational view thereof.

The broken line showing of a shoe upper and midsole in FIGS. 1-5 is for illustrative purposes only and forms no part of claimed design.
